UNITED STATES PATENT OFFICE.

PAUL C. BRENNER, OF CHICAGO, ILLINOIS.

ASH-SIFTER.

1,109,395.

Specification of Letters Patent. Patented Sept. 1, 1914.

Application filed September 23, 1913. Serial No. 791,340.

To all whom it may concern:

Be it known that I, PAUL C. BRENNER, a citizen of the United States, residing at Chicago, in the county of Cook and State 5 of Illinois, have invented new and useful Improvements in Ash-Sifters, of which the following is a specification.

This invention relates to ash sifters and particularly to sifters designed for direct 10 application to stoves, the object of the invention being to provide a device of this character which will include a foraminous movable member beneath the grate of the stove and an ash receiver beneath the foraminous member, the said foraminous member being mounted whereby it may be manually operated to permit the waste-matter 15 to be deposited into the ash receiver.

Another object of the invention is the 20 provision of a device of this character which will facilitate the sifting operation and effect a direct saving in the coal and eliminate the necessity of a subsequent sifting of the ashes after the latter are removed from 25 the stove.

Another object of the invention is to provide a light foraminous ash tray which will include a guard or shield for preventing the dust from escaping from the sifting compartment during the sifting operation.

With these and other objects in view, the invention consists of certain novel features of construction, combination and arrangement of parts, as will be hereinafter described and claimed.

In the accompanying drawings: Figure 1 is a front elevation of a stove, showing the application of the invention thereto; Fig. 2 is a section on line 2—2 of Fig. 1; and Fig. 40 3 is a section on line 3—3 of Fig. 2.

The device is designed for use particularly upon stoves designed for use in hotels, bakeries or large establishments where a direct sifting of the ashes on their discharge from 45 the grate results in a material saving in coal, but, however, it is to be understood that the device may be connected in any form of domestic stove or suitable coal consumer.

50 The stove 1 conventionally illustrated herein, is provided with the usual ash pit located directly beneath the grate 2 and divided into a main sifting compartment 3, an ash receiving compartment 4 and a receiving compartment 5, the latter being defined by adjacent walls of the stove and a

removable horizontal slide 6 on which the coal on its discharge from the grate may be first deposited and temporarily collected. This serves to permit the coals to be partly cooled before they are deposited onto the ash 60 tray. The slide is provided with a manipulating grip 7, which is located exteriorly of the front wall of the stove whereby it may be conveniently manipulated and adjusted to a position to permit the material to be 65 discharged into the compartment 3. The compartment 3 is provided with longitudinal side rails 8, on which rollers 9 of a sliding foraminous ash sifting tray are adapted to travel. This tray is provided with a solid 70 front, bottom portion 11 and shield forming front and top walls 12 and 13, the latter and the wall 12 being adapted to be projected through an opening 14 in the front wall of the stove and to form a closure for the opening 75 during the operation of reciprocating the ash tray. These parts just mentioned form a substantially rectangular shield or closure which is adapted to freely pass through the opening 14 to render the latter 80 dust-tight during the sifting operation. Beneath said foraminous ash tray and mounted in the compartment 4 is an ash receiving tray 15, which is adapted to be moved through an opening 16 in the front wall of 85 the stove so that it can be removed after the sifting operation. The wall 12 of the sifting tray carries a hand grip 17, which may be engaged by the hand and manipulated to impart sifting movements to the tray. Between the slide 6 and the sifting tray and 90 preferably extending at an angle from the front wall and in the direction of the sifting tray is a deflecting plate 18, which is adapted to insure the introduction of the waste material onto the foraminous bottom of the sifting tray. The slide 6 may be utilized as a damper, it being evident that it can be adjusted to a degree whereby to permit of the 95 required introduction of air beneath the grate.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention, as claimed.

Having thus described my invention, what I claim is:—

1. A sifting device for stoves comprising a horizontal slide mounted beneath the grate, a sifting tray slidably mounted in the stove, the stove having an opening disposed in line with the tray, a rectangular relatively wide shield movable in the opening and carried by the tray, a second tray mounted beneath the first tray, and a downwardly extending deflecting plate carried by the stove and underlying the slide and overlying the rectangular portion of the first tray.
- 10 2. An ash sifter for stoves, comprising an

impervious slide mounted within the stove 15 beneath the grate, a slidable tray mounted in the ash pit of the stove, a movable sifting tray beneath the slide and a deflecting member carried by the front wall of the stove and extending in the direction of the sifting 20 tray.

In testimony whereof I affix my signature in presence of two witnesses.

PAUL C. BRENNER.
